UNITED STATES PATENT OFFICE.

ELMER A. SPERRY, OF BROOKLYN, NEW YORK.

MULTIPLE-EXPANSION INTERNAL-COMBUSTION ENGINE.

1,325,810.

Specification of Letters Patent. Patented Dec. 23, 1919.

Application filed July 18, 1917. Serial No. 181,204.

To all whom it may concern:

Be it known that I, ELMER A. SPERRY, a citizen of the United States, residing at 1505 Albermarle road, Brooklyn, in the 5 county of Kings and State of New York, have invented certain new and useful Improvements in Multiple-Expansion Internal-Combustion Engines, of which the following is a specification.

10 This invention relates to internal combustion engines including those of the multiple expansion type, being of the general character disclosed in my U. S. Patent No. 1,041,985 of June 8, 1915. More particularly, this invention relates to an improved 15 means for supplying fuel and air to the engine, and for transferring the hot gases from the high to the low pressure cylinder.

Great difficulty has been experienced in 20 engines of this character in keeping the transfer valve between the high and low pressure cylinder sufficiently cool. It is one of the principal objects of the invention to provide an effective means for keeping the 25 said transfer valve cool without materially reducing the temperature of the transfer gases.

Another object of the invention is to provide an improved means for injecting the 30 fuel into the high pressure cylinder by means of air under very high pressure. The great degree of compression required is preferably achieved in several stages and a cooling of the air effected between some 35 or all of the stages. Various details of construction have also been improved whereby the engine has been especially adapted for use in propelling submarines.

Referring to the drawings in which what 40 I now consider to be the preferred form of my invention is shown:

Figure 1 is a vertical section of a compound engine constructed according to my invention, the section being taken on line 45 1-1 of Fig. 2.

Fig. 2 is a plan view of the same.

Fig. 3 is an enlarged plan view of one of the combined transfer and inlet valves.

Fig. 4 is a vertical section of the same on 50 line 4-4 of Fig. 3.

Fig. 5 is a vertical section of the same on line 5-5 Fig. 3.

Fig. 6 is a horizontal section of the valve on broken lines 6-6 of Fig. 4.

Fig. 7 is a detail of the valve operating mechanism.

Fig. 8 is a vertical section of the fuel feeding valve.

Fig. 9 is an elevation partly in section of the cooling means used to cool the air used 60 for injecting over or in contact with the valve between the high pressure cylinder and the super-compressor.

Fig. 10 is a section on line 10-10 of Fig. 8. Figs. 11 and 12 are details of construction.

To illustrate my invention, I have taken the compound engine illustrated in Figs. 1 and 2 in which two high pressure or combustion cylinders 1 and 2 are shown as 70 placed on opposite sides of the large low pressure or expansion cylinder 3, whereby a symmetrical arrangement is secured. All the cylinders are suspended from a composite end plate 200, being detachably secured thereto by means of bolts 201 (Figs. 2 and 12). Said plate is shown as supported from the base or bed plate 202 by end columns or rods 203 and central columns 204. Preferably the lower end of at least the low 80 pressure cylinder is guided or braced by said columns (see Fig. 1). For this purpose ears 205 may be provided thereon, which are bolted or otherwise secured to the columns 204. By such a construction any cylinder 85 may readily be detached without removing the end plate 200, thereby effecting a great saving in the headroom required. The pistons 4 and 5 of the high pressure cylinders are connected to the crank shaft 6 by piston rods 7-8; while the piston 9 of the low pressure cylinder is connected to said shaft by piston rod 10. Detachable wrist pins 206 and 207 secure the piston rods to the pistons.

By removing the extension pieces 208 on the 95 smaller cylinders or the hollow member 209 on the large cylinder, the pins may be easily driven out and the pistons removed. These particular features of engine construction, while forming a part of this invention, are 100 not claimed specifically herein but are reserved for a divisional application about to be filed.

A fly wheel 104 is shown as bolted to the

shaft 6. The exhaust valves for the low pressure cylinder are indicated at 115 and 116. The said valves are operated simultaneously by any suitable means such as link 5 150 connecting two short bell crank levers 151 and 152, the latter having a roller 153 bearing upon cam 154 on the cam shaft in the usual manner. Preferably the intake air for the high pressure cylinders is compressed 10 before being admitted thereto. This may be accomplished by employing the under side 11 of the low pressure piston 9 as an air pump, the admission of the air being controlled by puppet valve 12 and the discharge 15 controlled by a puppet valve 13.

From valve 13 the air is led through a pipe 14 into the reservoir or tank 15. From here it is carried by means of pipes 16 and 17 (see Fig. 2) to the air supply valves 18 20 and 19.

The two transfer valves 20 and 21 are preferably located adjacent thereto and may be made as a part thereof, so that the two valves may be bolted into openings in the 25 top of the engine. Leading to each of said pairs of valves from each high pressure cylinder is a restricted passage 22. Both the passage and high pressure cylinder are preferably water jacketed as indicated by 30 the slots 100 and 101 in their walls. Said passage 22 opens into the low pressure cylinder through opening 23 which is normally closed by the valve 20. The passage also extends across the top of valve 20, to the 35 valve 19 which is shown as composed of two valves and valve stems 25 and 26 (see Figs. 3, 4 and 5). The stem 27 of the valve 21 is shown as supported in a hollow bushing 28 which is preferably provided with cooling 40 ribs 29 thereon. Adjacent its upper end said stem is provided with a small piston 30 working in a chamber 31. The upper side of said chamber is in communication with the low pressure cylinder by means of a 45 hole or bore 32 through the valve stem, while the lower part is in communication with passage 22 by means of bore 33. By this means the back pressure on the valve is reduced so that it may be readily opened and 50 closed. The valve is shown as normally pressed on its seat by coiled spring 34, and is lifted to permit an exchange of gases between the cylinders by means such as bell crank lever 35 which has its outer end 55 forked and engages the stem 27 between shoulders 36 and 37 thereon while its inner end may be provided with a roller 103 engaged by a cam 38 on the cam shaft 39 of the engine. Said shaft may be driven from 60 the crank shaft 6 by any suitable means such as a gear 120 in case 121 on said shaft 6 which drives shaft 39 through gears (not shown) in casing 122.

The two valves 25 and 26 are preferably 65 operated together from an arm 40 pivoted

at 41 and having at its inner end a roller 105 engaging a cam 42 on shaft 39. Pins 106 and 107 are shown as threaded in the end of said lever and bear on the tops of the valve stems. Said valves are normally 70 maintained up against their seats and against said pins by springs 43 and are designed to operate alternately with the transfer valve 21. The supply air coming through pipe 16 into said valve circulates 75 through chamber 44 within hollow member 28 around cooling ribs 29 down through opening 45 and then around the bushing and out the opening 46, normally closed by the valve, thence through passage 22 over 80 the top of valve 21 and thence into the high pressure cylinder. When the inlet valve closes however and the transfer valve opens, the hot gases from the high pressure cylinder surge through the passage 22 and 85 opening 20 into the low pressure cylinder.

Preferably the opening of the transfer valve is so timed that the low pressure piston is approaching the top of the upward stroke. Furthermore the exhaust 90 valves 115 and 116 of the low pressure cylinder are closed before the end of the upward stroke of the piston 11 is reached. This results in the pressure in the low pressure cylinder becoming approximately 95 equal to the terminal pressure in the high pressure cylinder at the time the valve is opened, and also so that the terminal temperatures are approximately equal. By so timing the valves and movements I avoid 100 the possibility of momentarily opening either transfer valve when the opposite one is opened to admit the high pressure gases. Upon the opening of the last named valve the compressed gases suddenly fill the small 105 clearance at the top of the low pressure cylinder and tend to lift the closed valve and blow into the other high pressure cylinder for a moment before the equalizing 110 of the pressure on the two sides of the valve through the opening 32 can take place. On the other hand, when the pressure in the low pressure cylinder is brought up to approximately that of the high pressure cylinder before port 23 is uncovered, the increase 115 in pressure would be sufficiently gradual to permit the pressure on the two sides of the valves to be equalized through passage 32, so that there would be no tendency to open the closed transfer valve, as explained. The 120 advantage is also secured by this means that the clearance in the expansion cylinder need not be reduced to a minimum but may and preferably is fairly large and also that erosion of the valves and seats is lessened. 125 This feature is not claimed broadly herein, however, but is reserved for a copending application 312,193 for valve mechanism for internal combustion engines, filed July 21, 1919.

It will readily be seen that the successive passage of the comparatively cool incoming air over the top of the valve and also around the valve stem will reduce its temperature 5 sufficiently to prevent the hot transfer gases from damaging the same. At the same time the valve will not be cooled to a sufficiently low temperature to seriously reduce the temperature of the transfer gases.

10 After the given quantity of air supply is admitted to the high pressure cylinder, the valves 25 and 26 are closed and the air in the cylinder compressed. Since the supply air has been already compressed by the piston 11 as explained, the additional compression in the high pressure cylinder raises the pressure to a fairly high degree. In order to supply fuel in the engine under these conditions I prefer to make use of air which is 15 compressed to an even greater extent. This super-compression, as it may be termed, may be accomplished in many ways, but is preferably accomplished in several stages to avoid excessive heating thereof. I prefer 20 to abstract a small portion of the air compressed in the high pressure cylinder and to further compress the same in a small pump 50 which is located on top of the engine and driven from an eccentric 51 on the cam shaft 25 30. Said air is shown as taken out of the high pressure cylinder at 52 and lead to the pump 50 through pipe 110 and a cooling means or coils 53, designed to cool the air before being further compressed and thereby 35 further increase the advantages obtained by a multi-stage compression.

The air is shown as led through a plurality of pipes 54 which are located within a casting 55 through which water or other cooling 40 fluid is adapted to circulate. Apertures for the entrance and egress of the water are shown at 111 and 112 (Fig. 9). The air is then led into the side of the pump through pipe 56 and port 56'. The action of piston 45 50' in covering and uncovering port 56' times and governs the amount of air taken from the high pressure cylinder, the air being withdrawn preferably near the end of the compression stroke of the piston 4. 50 From the pump, the air is led to the fuel valve 57 through pipe 58. A pipe 210 is shown connecting the two pipes 58, which acts as a reservoir and equalizer. The said valve is shown as comprising central valve 55 stem 59 having a valve 60 adjacent its lower end which is held on seat 61 by spring 62 or the like. Surrounding said stem is a cylindrical member 63 normally held down by a strong spring 119 and having flutes 117 60 therein down which the incoming air and fuel are forced. The fuel is introduced through the pipe 64 from the fuel pump 118 into the small opening 65 and flows down into the chamber 66. As soon as the 65 valve opens the fuel is atomized and blown

out into the cylinder by the highly compressed air. The said valve is shown as operated by lever 67 rocked by shaft 39 in a manner similar to the operation of the other valves.

70 In accordance with the provisions of the patent statutes, I have herein described the principle of operation of my invention, together with the apparatus, which I now consider to represent the best embodiment 75 thereof, but I desire to have it understood that the apparatus shown is only illustrative and that the invention can be carried out by other means. Also, while it is designed to use the various features and elements in the 80 combination and relations described, some of these may be altered and others omitted without interfering with the more general results outlined, and the invention extends to such use.

85 Having described my invention, what I claim and desire to secure by Letters Patent is:

1. In an internal combustion engine, the combination with a cylinder, a valve therefor having a portion thereof exposed to the cylinder gases and a stem, means for conducting and dissipating heat rapidly away from said valve through said stem including a metallic casing in which the stem is movable, and an intake passage and valve adapted to guide the current of incoming air into contact with said casing and stem.

90 2. In an internal combustion engine, the combination with a cylinder having a large clearance including a passage, a unitary structure containing an exhaust valve having a stem and an intake valve located in said passage, means for opening and closing said valves during the cycles of operation, said valves being located adjacent each other and to the cylinder so that the intake air passes over said exhaust valve and stem to cool the same.

95 3. In an internal combustion engine, the combination with a cylinder having a large clearance including a passage, a unitary structure containing an exhaust valve and an intake valve in said passage, means for opening and closing said valves during the cycles of operation said valves being located adjacent each other and to the cylinder with the intake valve farther therefrom than the exhaust valve.

100 4. In a multiple expansion engine, the combination with a high and a low pressure cylinder, of a transfer gas valve therebetween, an exhaust valve for the last named cylinder and means for causing a circulation of other gases or air in contact with said transfer valve to cool the same.

105 5. In a multiple expansion engine, the combination with a high and a low pressure cylinder, of a transfer valve therebetween having a stem, and an intake valve for the 110

high pressure cylinder, said intake being so located as to cause the intake air to cool said valve and stem.

6. In a combustion engine, the combination with a cylinder, of an exhaust valve therefor having a stem, a plurality of inlet valves, and an inlet passage connected therewith, said inlet passage being arranged so as to cause the incoming air to pass into close proximity to and on either side of said exhaust valve and stem to cool the same.

7. In a combustion engine, a high pressure cylinder, of an exhaust valve therefor, means for opening and closing said valve during the cycles of operation, an air pump and means for passing a current of cooling fluid from said pump over said valve whenever it is closed.

8. In an internal combustion engine, the combination with two combustion cylinders and a common expansion cylinder, a transfer valve located between each combustion cylinder and the expansion cylinder, each valve having a plurality of surfaces, and means for alternately causing a circulation of cooling gases or air into contact with the surface of each valve to cool the same.

9. In a multiple expansion engine, the combination with a high and a low pressure cylinder, of a transfer valve therebetween, means for opening and closing said valve during the cycles of operation, and means for passing a current of cooling fluid over said valve when it is closed.

35 10. In a multiple expansion, the combination with a high and a low pressure cylinder, of a transfer valve therefor, an inlet valve for the high pressure cylinder located adjacent said transfer valve, a common passage behind said transfer valve for the incoming and transfer gases and means for opening and closing said valves alternately.

11. In a multiple expansion internal combustion engine, the combination with a plurality of high and low pressure cylinders, of transfer gas valves between each high pressure cylinder and the low pressure cylinder, each of said valves being provided with an equalizing passage, an exhaust valve for the low pressure cylinder, and means for closing said valve before the piston reaches the end of its stroke whereby the pressure in the low pressure cylinder is substantially equal to the pressure in the high pressure cylinder at the time either transfer valve is opened.

55 12. In a combustion engine a multi-stage compression for the air supplying the com-

bustion cylinder, a multi-stage expansion for the hot products, and coöperating valves acting between the stages on both the compression and expansion portions of the cycles, the portions handling the hot products being vigorously washed by the said compressed air supply.

60 13. In a combustion engine a multi-stage compression for the air supplying the combustion cylinder, a multi-stage expansion for the hot products, and coöperating valves acting between the stages on both the compression and expansion portions of the cycles, the portions handling the hot products being vigorously washed by the said compressed air supply and being less in extent than those portions of the valve exposed to the said air.

70 14. In a combustion engine a multi-stage compression for the air supplying the combustion cylinder, a multi-stage expansion for the hot products, and a coöperating valve arrangement acting between the stages on both the compression and expansion portions of the cycles, the portions handling the hot products being vigorously washed by the said compressed air supply, and being provided with extended surfaces in the path of the said compressed air supply.

75 15. In a combustion engine a multi-stage compression for the air supplying the combustion cylinder, a multi-stage expansion for the hot products, and coöperating valves adapted for intensive heat exchange acting between the stages on both the compression and expansion portions of the cycles.

80 16. In a combustion engine a multi-stage compression for the air supplying the combustion cylinder, a multi-stage expansion for the hot products, and a coöperating valve arrangement acting between the stages on both the compression and expansion portions of the cycles, the said valve arrangement being such that the portion handling the hot products delivers its heat to the incoming air.

85 17. In a multiple expansion engine in which the intake air is precompressed, a transfer valve, a valve part adapted to conduct heat rapidly away from the exposed parts of the valve, and an intake valve adjacent thereto having a passageway leading thereto adapted to cause the air to pass in contact with said part as it enters the engine.

100 In testimony whereof I affix my signature.

ELMER A. SPERRY.
